FORK OR SIMILAR ARTICLE OF FLATWARE

Siro R. Toffolon, Meriden, Conn., assignor to The International Silver Company, Meriden, Conn., a corporation of Connecticut

Filed Oct. 18, 1966, Ser. No. 4,319

Term of patent 14 years

(Cl. D54—12)

FIG. 1.

FIG. 2.

FIG. 3.

FIG. 4.

FIG. 5.

FIG. 1 is a front elevational view of a fork showing my new design;

FIG. 2 is a rear elevational view;

FIG. 3 is a side elevational view;

FIG. 4 is a cross-sectional view taken on line 4—4 of FIG. 1, showing the ornamentation applied to the face of the handle to be incised; and

FIG. 5 is a cross-sectional view taken on line 5—5 of FIG. 1.

The essential features of my design for a fork or similar article of flatware reside in the configuration of the handle in combination with the particular pattern of surface ornamentation applied thereto. The surface shading in FIG. 1 represents a florentine finish.

The design is intended for use on sets comprising forks, spoons, knives and similar articles of flatware.

I claim:

The ornamental design for a fork or similar article of flatware, substantially as shown and described.
